UNITED STATES PATENT OFFICE.

JAMES M. BUTCHER, OF CHICAGO, ILLINOIS.

AIRSHIP.

1,242,766.

Specification of Letters Patent.

Patented Oct. 9, 1917.

Application filed October 25, 1915. Serial No. 57,686.

To all whom it may concern:

Be it known that I, JAMES M. BUTCHER, a citizen of the United States, residing at Chicago, in the county of Cook and State 5 of Illinois, have invented certain new and useful Improvements in Airships; and I do hereby declare the following to be a full, clear, and exact description of the invention, such as will enable others skilled in the art 10 to which it appertains to make and use the same.

In its general aspects, my invention relates to conveyances moved by the action of propellers upon the fluid in which the conveyances move, one general object of my invention being to increase the effectiveness of action of the propelling means, and another object being to provide means for propelling a conveyance by the reaction upon a surrounding fluid of portions of said fluid projected in jets or vortexes at considerable pressures against other portions of the fluid. More particularly, my invention aims to provide airships and submarines with means 25 whereby the raising and lowering may be accomplished independently of planes, vanes or rudders, thereby permitting a substantially vertical ascent or descent of such conveyances and avoiding both the bulkiness 30 and the fragility of the planes heretofore used for transforming a horizontal into a partially vertical movement. Other objects are to provide propellers upon conveyances with means for checking a radially outward 35 movement of the surrounding fluid by the propellers, means for causing the action of each propeller to compress the actuated fluid considerably before the latter is discharged, means for affording an impact base of con- 40 siderable size for the discharged fluid, and means for automatically preventing a rapid movement of the fluid past the propellers in the opposite direction. Further objects will appear from the following specification 45 and from the accompanying drawings, in which—

Figure 1 is a plan view of a four-propeller airship embodying my invention.

Fig. 2 is a vertical transverse section 50 through the same along the line $a-a$ of Fig. 1.

Fig. 3 is a diagrammatic plan view of a five-propeller airship embodying my invention.

Fig. 4 is a side elevation of the embodiment of Fig. 1.

Fig. 5 is an enlarged fragmentary view of a propeller, showing portions of two of the blades and the closure vane interposed between the same. 60

Fig. 6 is fragmentary vertical section through Fig. 4 showing the arrangement of the driving mechanism.

Fig. 7 is a fragmentary view showing the use of a parachute as an alternative for the 65 safety flaps shown in Figs. 2 and 5.

While my invention may be applied with substantially equal advantages and effectiveness to widely varying types of crafts moving in either air or water (including aeroplanes, dirigible balloons, motor boats, submarines and automobiles) it is particularly adapted for use upon airships and is thus shown in the accompanying drawings, although I do not wish to be limited to the 70 embodiments or arrangements disclosed herewith. In each of the said types of crafts it has heretofore been customary to use propellers freely immersed in the actuated fluid, these propellers being usually of a helical 75 type and laterally exposed so that the action upon the surrounding fluid resolves itself partly into a thrust axially of the propellers and partly into thrusts radially outward of the latter. Owing to this division of direc- 80 tions, the power of each propeller is usually only partly utilized for the desired propul- 85 sion, this being particularly so in air where the fluid particles intermingle more easily than in water. To reduce this waste of power, I surround each propeller with a casing extending rearwardly thereof or in the direction in which the fluid is moved by the propeller, each casing being prefer- 90 ably composed of two frusto-conical por- 95 tions joined to each other at their smaller ends. For aerial navigation, I preferably use both vertical and horizontal propellers, so as to obtain both the vertical and the horizontal movement by the reaction upon 100 the surrounding air of the air moved by the respective propellers. For example, Fig. 1 shows an airship having a body 1 carrying two propellers 2 mounted on vertical shafts 3 and two propellers 4 mounted on horizon- 105 tal shafts 5, the respective shafts being all driven by a common engine 6 disposed under the aeronaut's seat 7 and being controlled by suitable clutches not shown in the draw- 110 ings. Each of the propellers is preferably mounted at the mouth or larger end of a frusto-conical casing 8, which casing may

have an oppositely tapering extension 9 attached to its smaller end, and each casing is supported by suitable frames 10 secured to the body 1 of the airship. Each propeller preferably has its blades tapered at their ends (as shown in Fig. 2) so as to barely clear the interior of the tapering casing 8 and also preferably has a tapering flap or vane 11 pivoted to the forward edge 10 of each blade as shown in Fig. 5.

When the propeller of Fig. 2 is set in motion with the blades rotating in the direction in which they would tend to screw themselves upwardly into the air, this rotation will draw air into the casing 8 and to partially rotate this air within the casing. There, the air will encounter the friction of the casing and owing also to the downwardly diminishing diameter of the casing 8, this air will be considerably compressed by the time it is discharged from the lower end of the casing 8. When thus discharged at considerable pressure and with a velocity depending upon the speed at which the propeller is rotating, the impact of the emitted air against the ground (when the airship is standing still) or against the outer air (when the airship is aloft) will create a reaction causing the propeller 2, and therefore 20 the body to which the latter is connected, to rise in the air. By placing two such propellers forward and aft upon the body of the air ship and rotating them simultaneously and uniformly, the conveyance can 25 readily be raised horizontally; or, if the craft is in the air and the speed of rotation of the propellers is reduced below the point required for the lifting, the airship will gradually descend. Likewise, by running 30 one of the two propellers 2 at higher speed than the other, the airship may be raised obliquely without the use of planes, vanes or rudders. So also, by running the propellers 4 either synchronously or otherwise, 35 the air ship may be moved horizontally either in a straight line or in curves controlled by the relative speed of the two propellers.

However, while I am thus able to effect 40 vertical and horizontal movements independently of each other entirely by means of the propellers, I preferably also provide my craft with independently controlled lifting vanes or horizontal rudders 12 and with 45 a rear rudder 13, each of which may easily be manipulated by means familiar in aeronautical practice and not shown in the drawings. I also preferably drive the propellers 2 in opposite directions (as, for example, by means of the shafts and bevel gears shown in Fig. 1), so that they will 50 counteract each other in any rotational effect upon the body of the craft.

It will be obvious from the drawings that 55 each of the casings, while freely admitting

the air to the corresponding propeller, laterally houses the latter and causes it to concentrate the air in a jet. Thus, each casing practically forms a nozzle within which air is compressed and from which air is ejected 70 with a vortex motion and under considerable pressure against the adjacent outer air. To give each jet a sufficiently large impact base, each casing 8 may have a relatively short and rapidly flaring extension 9 secured to 75 its nozzle end. However, I do not wish to be limited to this arrangement, nor to the proportions or other details as herein disclosed, nor to the pivoted safety flaps 11 carried by the propeller blades. When each 80 propeller is rotating, the impact of the entering air against these flaps will swing the latter back under the blades to which they are pivoted, as shown in dotted lines in Fig. 5, so that they will be substantially out of 85 the way. However, when the propeller stops rotating, the flaps 11 will drop by gravity into the position of Fig. 5 and will be held there by the upward pressure of air passing through the casing 8 in case a disabled engine causes the airship to fall. Consequently, air will only be able to pass through the vertical tubes as fast as the same can 90 seep through the relatively small openings between the periphery of the blades and the 95 adjacent parts of the casings, thus impeding the descent of the craft in case of accidents.

While I have described and pictured my invention as applied to a craft movable in 100 air, it will be obvious that the action of the casings and flaps will be substantially the same for a watercraft, so that these features might be applied with equal advantages to submarines or other boats. So also, it will 105 be evident that the number, size and arrangement of both the vertical and the horizontal propellers might be varied greatly without departing from the spirit of my invention. For example, the diagram of Fig. 110 3 shows a craft having four propellers on vertical axes and one relatively large propeller on a horizontal axis.

So also, Fig. 7 shows a cylindrical casing 115 housing a propeller and a parachute 14, which latter might serve as a substitute for the safety flaps 11 in substantially closing the casing so as to prevent a rapid upward movement of air past the propeller.

I claim as my invention:

1. In an airship, the combination with a casing comprising a long and straight-sided tapering tube and a relatively short tapering tube adjoined to the smaller end thereof, of a propeller disposed within the larger end of the first named tube, and movable flaps carried respectively by the propeller blades and normally closing the gaps between successive blades to afford a closure substantially flush with the larger end of 130

the first named tube, said flaps so disposed as to be moved out of their said closure positions by the normal rotation of the propeller.

5 2. In a conveyance, the combination with an actuating helical propeller, of a casing housing the same and comprising an acute-

angled straight-sided tube tapering from a portion disposed laterally of the propeller, and an obtuse-angled and relatively shorter-¹⁰ straight-sided tube united at its smaller end to the smaller end of the aforesaid tube.

JAMES M. BUTCHER.
